UNITED STATES PATENT OFFICE.

MARTIN BRIGGS, OF ROCHESTER, NEW YORK.

IMPROVEMENT IN BOLT-WORKS FOR SAFE AND VAULT DOORS.

Specification forming part of Letters Patent No. 149,193, dated March 31, 1874; application filed February 17, 1874.

To all whom it may concern:

Be it known that I, MARTIN BRIGGS, of Rochester, in the county of Monroe and State of New York, have invented certain new and useful Improvements in Bolt-Work for Fire-Proof Safes and Vault-Doors, of which the following is a specification:

This invention relates to a system of bolt-work for closing the crevice or space between the door and casing of a safe, in order to prevent the entrance of fire and water, and the operation of burglars.

This invention consists in applying, to the back plate of a fire or burglar proof safe, an upper and lower horizontal plate having vertical arms, each of which arms is provided with a double rack, arranged in relation to pinion-arbors, for operating the said arms and plates to cause them to have a vertical movement, so that they can be projected into a recess in the door-casing, or withdrawn therefrom, as hereinafter described. The invention also consists in arranging, on the back of the safe-door, vertical sliding plates or bolts, each plate having two horizontal arms provided with racks, arranged in relation to the operative pinions, and combined with upper and lower horizontal plates having vertical arms, each provided with double racks, which mesh into the said pinions, in such a manner that by rotating the pinions the plates are caused to have a simultaneous and positive vertical and horizontal motion imparted to them, as hereinafter described.

In the drawings, Figure 1 is an elevation of the back of a safe-door, representing my bolt-work applied thereto, and also a section of the door-casing. Fig. 2 is a detail view, representing the form and arrangements of the bolts.

The body A of the safe and the door B are constructed in the usual manner, and the latter is provided with suitable locking devices, in addition to the bolt-work for closing the space between the door and the casing, which forms the subject-matter of the present invention. To the back plate of the safe-door are applied a series of bolts or sliding plates, two of which, lettered C C, are located, respectively, at the top and bottom of the door, so as to move in a vertical plane. At the sides of

the door are arranged two corresponding plates or bolts, C' C', which move horizontally in respect to the door and casing. The plates or bolts C C are each provided with a vertical arm, D, having near the top and bottom a series of teeth or rack-surfaces, c d c' d', and the plates or bolts C' C' are provided with double horizontally-projecting arms D' D', which are formed with rack-surfaces e e' f f' near their outer or free ends. The plates arranged around the margin of the door, as described, are designed to be forced in an outward direction from the door-frame, for causing the same to enter grooves or recesses in the door-casing, in order to close the crevice or space left between the edges of the door and the mouth in the door-frame, by which means the safe is rendered proof against the entrance of fire and water, and the attacks of burglars. The sliding bolts or plates are guided or steadied in their movement by fixed studs or pins a, which pass through slots b, made in the bolts and in the arms of the same. A positive and perfect movement is imparted to the bolt-work through the medium of a pair of pinion-arbors, F F, to one of which is applied a knob or handle for turning the same. The teeth of the pinion-arbors are made long enough to engage both with the arms of the bolts which move vertically and horizontally. One pinion is, therefore, made to engage with the rack-surfaces d and c' of the vertically-movable arm, and the corresponding racks e e' of the upper arms of the horizontally-sliding bolts, while the other pinion gears into the racks c d' and f f' of the vertically and horizontally moving bolts. The arms of one pair of the bolts are bent in the manner shown at H, so as to form a central space for the reception of a lock, G, which is employed for retaining the bolts in a locked position after they have been projected into the door-casing.

The pinion-arbors and rack-arms, combined with the locking-bolts, as proposed by me, will permit the latter to be operated in a most perfect and expeditious manner, thus enabling the bolts to be projected into the grooves or recesses formed in the door-casing, or to be retracted therefrom with the greatest ease and facility. The bolt-work for closing the crevice or space between the door and its casing is

used as an auxiliary device in connection with either permutation or other locks, thus enabling safes to be protected in a perfect manner. The bolt-work, being attached directly to the back plate of the door, is exposed to view, and can be readily applied in position.

What I claim is—

1. The plates C C, having arms D, each arm having double racks, as shown, when combined and arranged in co-operative relation to the operative pinion-arbors F F, and adapted to be applied to the back of a fire or burglar proof safe or vault door, substantially as and for the purpose set forth.

2. The plates C' C', having double arms D' D' and racks e e' f f', combined with the operative pinions F F and plates or bolts C C, having arms D and racks c d, substantially as described, for the purpose specified.

In testimony that I claim the foregoing I have hereunto set my hand this 2d day of February, 1874.

MARTIN BRIGGS.
